AIR HUMIDIFYING APPARATUS

Seth Mauritz Fingal Engdahl, Stockholm, Sweden

Application June 14, 1933, Serial No. 675,747
In Sweden June 23, 1932

7 Claims (CL 261—89)

This invention relates to an apparatus for humidifying and also for heating or cooling air. Such apparatus are old. As a rule such devices operate in such a manner that a current of 5 warm, tempered or cool air is forced through the apparatus to pass in such intimate contact with a body of water or water spray that when the air leaves the apparatus it is completely or almost completely saturated with moisture.

When it is desired to maintain high moisture content of the air in a room with considerable evolution of heat, the air, which flows out into the room through the humidifying apparatus, should also contain an excess of water in the 10 form of mist or extremely small drops, which are then allowed to be absorbed by the air in the room. It is very difficult to obtain this result since the excess of moisture is easily carried out in the form of large water drops by the air 15 leaving the apparatus, and these water drops cannot be absorbed by the air in the room quickly enough. In order to effect the intended mechanical delivery of the moisture in a finely 20 divided form it is necessary that air and water spray be repeatedly brought into an intimate 25 contact with each other in a specific manner in the humidifier whereupon the largest water drops will be separated before the air is allowed to flow out freely into the room.

The present invention relates to a humidifying apparatus which, in spite of relatively simple construction, works efficiently as to the quantity 30 of water absorbed per unit of volume by the passing air, whereby large rooms may be kept at a relatively high humidity by means of a relatively small quantity of air projected by one or more humidifiers.

The accompanying drawing shows schematically an embodiment of the apparatus. Fig. 1 35 is a vertical section of the apparatus, Fig. 2 is a cross section taken on line II—II of Fig. 1, and Fig. 3 is a plan view, the left portion of the apparatus being shown in a horizontal section, along the line III—III of Fig. 2. Fig. 4 shows 40 a vertical section on a larger scale of an embodiment of the apparatus. Fig. 5 shows a section taken along line V—V of Fig. 4.

In the drawing numeral 1 indicates a box and a fan casing respectively, through which fresh 45 air or circulation air to be humidified, is forced by means of a fan wheel or propeller 2. The driving motor is indicated at 3. Shaft 4 of the motor is vertically journaled and carries also a disk 5. Below the fan there is an intermediate 50 wall 6 having a suction opening 6a. 7a indi-

cates a filter which in certain cases may be necessary for cleansing the air entering through the inlet 7. 8 indicates a heater for the air. A water container 9 is provided with a float valve and has an overflow outlet 10. A pipe 11 leads 5 from the container to the disk 5, see Fig. 1.

The pipe 11 is provided with a control valve 12 and it has the outlet opening 13 at a lower level than the water level in the container 9. 9a indicates a filtering device provided with a faucet 9b. The inner surface of the casing 1 is provided with a collecting channel 14, see Fig. 1. A return conduit 15 leads from the channel 14 to the upper side of the fan 2. The intermediate wall 6 has a level tube 16 adapted to 15 be raised and lowered in vertical direction, the said tube leading the excess water to the bottom of the casing 1 which is provided with outlet pipe 17.

The apparatus is provided with an exhaust 20 and distributing drum 18, see Fig. 1, for the air. In this drum there is arranged a longitudinally extending opening 19, formed by intermediate plates 20, the edges of which are formed as drop catchers 21 (see Fig. 2). Exhaust canals 23 for 25 the air are formed by the top plate 22, the channel-shaped intermediate bottom 20 and by slanting guide rails 24 located in the intermediate space between the two.

The apparatus according to Figs. 1, 2 and 3 30 operates as follows:

The air is forced through the apparatus by the fan wheel 2 and thus flows through the opening 6a of the intermediate wall 6 and out through the exhaust drum 18. The water for 35 humidifying the air escapes through the pipe 11 down onto the disk 5 which rotates rapidly. Due to the influence of the centrifugal force the disk throws the water to the side forming a veil or a very thin layer across the intermediate 40 space between the disk and the walls of the fan casing. Part of the water is absorbed by the passing air and part of it is caught by the collecting channel 14.

The water thus caught flows through the pipe 45 15 down onto the upper side of the fan wheel and thus comes in a finely divided state into intimate contact with the air current. A layer of water formed on the intermediate wall 6, is rotated by escaping water and air and by the 50 effect of the centrifugal force the height of the water layer increases away from the center of the opening 6a. The height of the water layer is controlled by means of the level pipe 16. 55 When the air is sucked into the fan wheel

through the opening 6a of the wall 6 very rapidly, water is forced from the wall 6 and also some of the air above the water. This mixture of air and water passes through the fan wheel 5 along with newly sucked-in air, which is also mixed with water. The surfaces of the fan wheel are always kept damp in this way, and when the quantity of water which is not absorbed by the air during its passage through the fan wheel, is 10 thrown out again, a circulating current of spray is obtained through the fan wheel along with the passing air.

The water and air are brought into intimate contact with each other owing, partly to the 15 fact that the air is caused to pass repeatedly through spray, and partly that it is caused to come into contact with surfaces damped by spray. The output of the apparatus is thus increased without a great deal of excess water. 20 The air is pushed through the exhaust drum 18 into the room. At this point it is caused to pass through the slot 19 where large water drops, which may have been carried out, are separated by the said drop catcher 21. The air is now 25 suitably directed to escape into the room depending on the slant of the top plate 22 and the guide rails 24. The apparatus may be made with a plurality of disks 5. The exhaust drum 18 may of course also be formed for air exhaustion 30 only at one side.

Figs. 4 and 5 show another embodiment of the apparatus. The disk 5 of Fig. 1 has been removed, and the water from the tube 13 flows directly down onto the upper side of the fan 35 wheel 2. 2a indicates the vanes of the fan wheel.

In this embodiment the exhaust drum 18a is of another construction than in the embodiment shown in Fig. 1. 25 indicates a grate of a 40 known construction for separating large drops. The exhaust openings for the air are in this embodiment located in conical nozzles 26 tapering in the direction of the exhaust. In Figs. 4 and 5 only one such nozzle is shown although 45 the apparatus generally is made with a plurality of such nozzles. In the bottom of the nozzle 26 there is, adjacent to the escape opening, a shoulder or the like 27, behind which, viewed in the direction of the exhaust, water drops separated from the air have the air current pass over them without effecting them in order that they 50 may flow back gradually to the drum for the purpose of preventing drops separated at the mouth from being exhausted. The shoulder 55 may of course be formed by applying a special plate or by bending in a part of the wall of the nozzle or the like.

If during the cold season the air for humidifying is sucked into the apparatus from the outside 60 without first heating it, the apparatus may freeze up. Should this occur in the upper portion of the apparatus, the rotatable parts may be damaged. This risk is avoided by a device, by means of which the water supply is automatically shut off when freezing takes place. This is accomplished by passing the pipe conduit 11 through the lower portion of the apparatus, where it is surrounded by the air sucked in. The freezing will take place in the lower 65 portion of the pipe, whereby the water supply to the upper part is automatically stopped.

It is easily understood that by regulating and shutting off respectively the heat supply to the battery 8 one may cause warm, tempered or 70 cool air, saturated with moisture, to flow out

into the room, to which the apparatus is connected.

Having now described my invention, what I claim as new and desire to secure by Letters Patent is:

1. An air humidifying apparatus comprising a casing, at least one fan in said casing for creating a current of air; means for supplying liquid to said fan so that the liquid is spread by centrifugal force, and a surface below said fan for collecting surplus liquid spread by the fan but not absorbed by the air, said surface being formed with a suction opening for air, and said surface being so disposed relative to said fan that said surplus liquid is reintroduced into the air current by passing directly from the collecting surface to the fan. 10

2. In a humidifier according to claim 1, characterized by an adjustable level pipe in said surface. 20

3. In an air humidifier, a water supply, a propeller, a vertical shaft for said propeller, means for distributing in a mist water from said supply in the path of air current produced by said propeller, and a surface below said propeller for collecting water from said mist, said surface having an opening in alignment with said propeller and being disposed so that unabsorbed water which has been collected is reintroduced into the air current by suction force, including 30 a disc mounted on said shaft above said propeller and adapted to form part of said means for distributing water in a mist, a channel for collecting water below the level of said disc, and a pipe leading from said channel to the upper 35 side of said propeller.

4. In an air humidifier, a water supply, a propeller, a vertical shaft for said propeller, means for distributing in a mist water from said supply in the path of air current produced by 40 said propeller, a surface below said propeller for collecting water from said mist, said surface having an opening in alignment with said propeller and being disposed so that unabsorbed water which has been collected is reintroduced 45 into the air current by suction force, a casing surrounding said humidifier and having an air inlet opening, heating means adjacent said air inlet opening, and a pipe leading from said water supply through a zone adjacent said heating 50 means to a point above said propeller.

5. In an air humidifier, a water supply, a propeller, a vertical shaft for said propeller, means for distributing in a mist water from said supply in the path of air current produced by 55 said propeller, a surface below said propeller, for collecting water from said mist, said surface having an opening in alignment with said propeller and being disposed so that unabsorbed water which has been collected is reintroduced 60 into the air current by suction force, a casing surrounding said humidifier, an exhaust drum connected with said casing and having a bottom slanting towards said surface, and water-separating means in said drum. 65

6. In an air humidifier, a water supply, a propeller, a vertical shaft for said propeller, means for distributing in a mist water from said supply in the path of air current produced by said propeller, a surface below said propeller for collecting water from said mist, said surface having an opening in alignment with said propeller and being disposed so that unabsorbed water which has been collected is reintroduced into the air current by suction force, a casing surround- 70 75

ing said humidifier, an exhaust drum connected with said casing and having a bottom slanting towards said surface, water-separating means in said drum, conical exhaust pipes projecting from 5 said drum and tapering in the direction of the exhaust, and an inside shoulder in said pipes near their open ends.

7. In an air humidifier, a water supply, a propeller, a vertical shaft for said propeller, 10 means for distributing in a mist water from said supply in the path of air current produced by

said propeller, a surface below said propeller for collecting water from said mist, said surface having an opening in alignment with said propeller being disposed so that unabsorbed water which has been collected is reintroduced into the air current by suction force, a casing surrounding said humidifier, a reservoir forming part of said supply, a float valve in said reservoir, and an overflow in said reservoir connected with said casing.
